UNITED STATES PATENT OFFICE

JOHN VACHER, OF WATERBURY, CONNECTICUT, ASSIGNOR TO THE AMERICAN MILLS COMPANY, OF WATERBURY, CONNECTICUT, A CORPORATION

COVERING DEVICE FOR ELASTIC STRANDS, WIRE, AND THE LIKE

Application filed August 4, 1931. Serial No. 555,025.

This invention relates to an improvement in covering devices for applying a covering to strands of various materials, that is to say, devices for helically wrapping one or more 5 layers of covering upon strands of rubber, metal wire, etc., and relates in particular to the so-called "flyers" of such devices.

One of the main objects of my present invention is to provide a covering or wrapping 10 device capable of rapidly applying a covering to an elastic strand or the like, with particular reference to producing a uniform and smooth covering.

With the above and other objects in view, 15 as will appear from the following, my invention consists in a covering device having certain details of construction and arrangement of parts as will be hereinafter described and particularly pointed out in the claims.

20 In the accompanying drawings:

Fig. 1 is a view in side elevation of one form which a covering device embodying my invention may assume;

Fig. 2 is a top plan view thereof;

25 Fig. 3 is a corresponding view but showing the position which the "flyer" assumes when fabric is being drawn from the lower portion of the cop; and

Fig. 4 is a perspective view of the "flyer", 30 detached but on a larger scale.

The particular covering device herein chosen for the illustration of my invention consists, as shown, of a horizontally-arranged U-shaped frame 10, adapted to be secured to any suitable support in a covering machine and itself providing a support for a hollow 35 spindle 11 carrying at its upper end a cop-head 12 having, as shown, at its lower end an annular plate-like flange 13.

Secured to the lower end of the spindle 11 above referred to, by means of a set-screw 14, and located between the respective horizontal arms 15 and 16 of the U-shaped frame 10, 45 is a driving-pulley 17 by means of which the spindle, and hence the cop-head 12, is rapidly rotated.

The head 12 above referred to has sleeved over it in the usual manner of covering machines a cop-tube 18 carrying the usual cop-

19 of covering material, such as cotton, silk, etc.

Mounted upon the spindle 11, adjacent its upper end and with freedom for rotation thereon, is a collar-like flyer-hub 20, preferably formed of indurated fibre and provided in its periphery with an annular groove 21 for the reception of the central portion of a flyer, generally designated by the numeral 22 and preferably formed of piano wire, or 55 other equivalent resilient, filamentary material.

The central portion of the flyer 22 is wrapped or looped around the hub 20 in the groove 21 thereof, as above described, and 60 has its respective upper arm 23 wrapped around the portion of its lower arm 24 immediately adjacent the said hub, so as to be firmly attached thereto.

The upper end of the arm 23 of the flyer 70 is bent into helical form to provide an eye 25, while the central portion of the said arm is reversely bent to form a loop 26 to increase the resiliency thereof.

The lower arm 24 of the flyer extends horizontally outward from the hub 20 and is bent to form a loop 27 from which vertically depends the outer reach 28 of the said arm. The lower end of the reach 28 of the arm 24 is helically bent to form an eye 29 through 80 which a single or multiple thread 30, as the case may be, extends from the cop 19, thence diagonally upward and inward through the eye 25 of the upper arm 23 and thence around a strand 31 which is being covered. 85

The strand 31, to which the covering is being applied, extends vertically in the usual manner of covering machines, through the hollow interior of the spindle 11.

It will be understood that the spindle 11 90 is revolved by means of its pulley 17 and hence effects the rotation of the cop 19 to wrap the thread 30 around the strand 31 as the latter is being drawn upward through the hollow spindle at a predetermined rate 95 of speed.

One of the main requirements for the effective wrapping of the covering upon a strand, as above described, is the freedom of movement of the so-called "flyer." Now par- 100

ticular attention is called to the fact that in my improved covering device the flyer is of such shape and form that the cramping of the flyer-hub 20 upon the spindle 11 is reduced to a minimum by reason of the fact that the respective arms 23 and 24 of the flyer extend in opposite directions from the said hub, i. e., above and below the bearing-plane thereof.

10 The operation of my improved flyer may be best understood if it is observed that in drawing off the thread 30 from the cop 19, the lower reach A of the said thread tends to draw inward upon the eye 29 and hence tends to cant the hub 20 in a clockwise direction upon the upper end of the spindle 11. This tendency, however, to cant the hub as just described is offset by the draft upon the upper reach B of the thread as the latter 20 is being wrapped around the strand 31. The draft at this latter point serves to effectively counter the draft of the lower reach A of the thread and so results in a substantial equilibrium in which any appreciable 25 cramping of the hub upon the spindle is avoided.

Furthermore, by interposing the resilient loop 27 in the lower arm 24 of the flyer, the eye 29 thereof is enabled to travel vertically, 30 to a limited extent, as the thread is being drawn from the upper or lower portion, respectively, of the cop 19. The vertical movement of the eye 29 just referred to, while of limited extent, is sufficient to insure the uniform withdrawal of the thread from the cop, 35 which uniform withdrawal is essential to a uniform application of the thread to the strand 31.

It will be understood by those skilled in 40 the art that my invention may assume varied physical forms without departing from my inventive concept, and I, therefore, do not limit myself to the specific embodiment herein chosen for illustration, but only as indicated in the appended claims.

I claim:

1. A flyer for a device of the class described, consisting of a hub adapted to be rotatably mounted upon a spindle; a filamentary member looped around said hub and having its hub-adjacent portions interengaged to fix it to said hub, said member providing a pair of thread-guiding arms respectively extending above and below the 55 plane of the said hub.

2. A flyer for a device of the class described, consisting of a hub adapted to be rotatably mounted upon a spindle; an inherently resilient wire looped around said hub and having its hub-adjacent portions interengaged to fix it to said hub, said member providing a pair of resilient thread-guiding arms respectively extending above and below the 60 plane of the said hub, each of said 65 arms provided intermediate its ends with a

loop whereby the inherent resiliency of the arms is enhanced.

3. A flyer for a device of the class described, consisting of a hub adapted to be rotatably mounted upon a spindle; and a 70 pair of thread-guiding arms respectively extending above and below the plane of the said hub; the arm extending below the plane of the said hub having a free end provided with thread-guiding means and formed intermediate its ends with a closed loop substantially overlying said free end, said loop functioning to increase the resiliency of said arm and permit limited yielding movement of its thread-guiding means in a direction 75 substantially parallel with the axis of the said hub.

4. A flyer for a device of the class described, consisting of a hub adapted to be rotatably mounted upon a spindle; and a 80 pair of thread-guiding arms each provided with a thread-guiding eye respectively located above and below the plane of the said hub; the arm extending below the plane of the said hub being formed intermediate its 85 ends with a closed loop substantially overlying its thread-guiding eye to increase the resiliency of said arm and permit limited yielding movement of its eye in a direction 90 substantially parallel with the axis of the 95 said hub.

5. A flyer for a device of the class described, consisting of a hub adapted to be rotatably mounted upon a spindle; and a 100 pair of thread-guiding arms each provided with a thread-guiding eye respectively located above and below the plane of the said hub; the arm extending below the plane of the said hub being substantially L-shaped and bent to form an intermediate closed 105 looped portion substantially overlying its thread-guiding eye to increase its resiliency and permit limited yielding movement of its eye in a direction substantially parallel 110 with the axis of the said hub.

In testimony whereof, I have signed this specification.

JOHN VACHER.
